UNITED STATES PATENT OFFICE.

EMIL JOSSE, OF BERLIN-LANKWITZ, AND WILHELM GENSECKE, OF BERLIN, GERMANY,
ASSIGNORS TO GESELLSCHAFT FÜR KÄLTEINDUSTRIE MIT BESCHRÄNKTER HAF-
TUNG, OF BERLIN, GERMANY, A CORPORATION OF GERMANY.

DEVICE FOR CONDENSING AND VACUUM-PRODUCING.

1,208,325.

Specification of Letters Patent. Patented Dec. 12, 1916.

Application filed July 9, 1915. Serial No. 38,975.

To all whom it may concern:

Be it known that we, EMIL JOSSE and WILHELM GENSECKE, both citizens of the Empire of Germany, and residents, respectively, of Berlin-Lankwitz and of Berlin, Germany, have invented certain new and useful Improvements in Devices for Condensing and Vacuum-Producing, of which the following is a specification.

10 The object of the present invention is to provide an improved device for condensing and vacuum producing.

The invention has reference to such devices in which air and vapor are withdrawn by or with the aid of water supplied under pressure through a jet ejector arranged to deliver the water with the withdrawn air into a circulating tank or system from which the air can escape.

20 According to the invention besides the air and uncondensed vapor the water of condensation is withdrawn by a jet ejector of a circulating system. To gain good results the water of the circulating system must be cooled. According to our invention this is done by using the condensing water as cooling medium.

The accompanying drawing shows more or less diagrammatically an embodiment of 30 the invention.

a is a surface condenser, *b* is a jet ejector, connected to the air, vapor and condensate outlet from the condenser. The jet ejector *b* discharges air and water through a discharge-pipe *c* direct into the circulating tank *d*, so that upon the water and air being discharged into the tank, the air will rise and be liberated at the top as shown by the arrows in the drawing. The circulating tank *d* is provided with an overflow *g*.

f is a circulating pump for withdrawing water from the tank *d* and delivering it into the jet ejector *b* so that water is caused to circulate continuously through the jet ejector *b* and the tank *d*. The pipe for delivering cooling water into the condenser *a* enters the tank *d* where the pipe is formed into a coil *h*. The cooling water leaves the condenser *a* by the tube *i*.

50 Various modifications in the form shown and described may be made within the scope of the claims without departing from the spirit of our invention.

What we claim as our invention and de-

sire to secure by United States Letters Patent is:

1. In a condensing plant the combination of a surface condenser, cooling means for said condenser, a water circulating system independent of the cooling means, pressure means included in said system to maintain the circulation thereof, a jet actuated by the pressure means and arranged to withdraw air and condensate simultaneously from said condenser through a single discharge opening and an open tank in said water circulating system whereby air is permitted to pass off and a surface of evaporation is provided.

2. In a condensing plant the combination of a surface condenser, cooling means for said condenser, a water circulation system independent of the cooling means, pressure means for maintaining said circulation, the said cooling means being disposed to cool the water in said circulation system, jet producing means in said water circulation system adjacent to and actuated by said pressure means and arranged to withdraw air and condensate simultaneously from said condenser through a single discharge opening, an open reservoir in the circulation system to receive the discharge products of the jet.

3. In a condensing plant the combination of a surface condenser, cooling means for said condenser, a water circulation independent of the cooling means, a pressure pump to maintain said circulation, jet producing means in said water circulation system adjacent to and actuated by said pressure pump and arranged to withdraw air and condensate simultaneously from said condenser through a single discharge opening, and an open reservoir in the circulation system to receive the discharge products of the jet, the cooling means being disposed to cool the contents of said reservoir.

4. In a condensing plant the combination of a surface condenser, cooling means including a pipe section for said condenser, a water circulation system independent of the cooling means, a pressure pump in said circulation system, jet producing means in said water circulation system actuated by said pump and arranged to withdraw air and condensate simultaneously from said condenser through a single discharge opening,

and an open reservoir in the circulation system to receive the air and condensate removed by the jet, the pipe section of said cooling means passing through said reservoir.

5. In a condensing plant the combination of a surface condenser, a circulating cooling system for said condenser, a second circulating system entirely independent of the 10 cooling system, a pressure pump and a jet actuated thereby in said second system, a single pipe connection from a point beneath the water level of the condenser to said jet

through which all air and condensate must pass when drawn from the condenser, and 15 an open reservoir in said second circulating system, said cooling system passing through said reservoir.

In testimony whereof, we have hereunto set our hands.

EMIL JOSSE.

WILHELM GENSECKE.
